ABSTRACT OF THE DISCLOSURE

A practice bowling ball including an outer shell filled with a foam plastic material supporting a centrally positioned spherical weight. Some finger receiving recesses open through the shell and others are removably covered by reduced thickness portions of the shell so that different grips are available to a bowler.

The present invention relates to a plastic practice bowling ball. More particularly, the invention relates to a plastic practice bowling ball with selectable covered finger holes.

The principal object of the present invention is to provide a new and improved practice bowling ball. The bowling ball of the present invention is of sturdy, substantially unbreakable structure and is suitably balanced and lightly weighted so that it does not damage household objects and has the desirable characteristics of a practice bowling ball. The bowling ball of the present invention may be utilized for practice by bowlers with different sized hands and different finger sizes and separations with comfort and facility.

In accordance with the present invention, a practice bowling ball comprises a spherical shell of plastic material having a substantially uniform thickness with a plurality of finger holes formed therethrough and a plurality of finger hole areas formed therein in the vicinity of said finger holes. The thickness of the shell at each of the finger hole areas is less than the uniform thickness of the shell. A metal mass of spherical configuration is positioned at the center of the shell substantially radially equidistant from the shell. The metal mass is supported in the shell by foam plastic material filling the shell between the metal mass and the shell.

In order that the present invention may be readily carried into effect, it will now be described with reference to the accompanying drawing, wherein:

FIG. 1 is a view of an embodiment of the practice bowling ball of the present invention; and

FIG. 2 is a sectional view of the embodiment of the practice bowling ball of the present invention, taken along the lines II—II of FIG. 1.

In the figures, a spherical shell 11 of plastic material has a substantially uniform thickness t . A plurality of finger holes 12 are formed through the shell 11. A plurality of finger hole areas 13 are formed in the shell 11 in the vicinity of the finger holes 12. The thickness tt of the shell 11 at each of the finger hole areas 13 is less than the uniform thickness t of said shell.

The thickness t of the shell 11 is sufficient to make said shell sturdy and substantially unbreakable. The thickness tt of the shell 11 at each of the finger hole areas 13 is small enough so that it may be readily perforated and removed by a bowler. When the thickness tt of the shell 11 is broken and removed by a bowler, it uncovers or opens a finger hole, which is formed in said shell under the corresponding finger hole area. Thus, if the practice bowling ball is to be utilized by more than one bowler, or if a bowler finds that the finger holes are uncomfor-

2

ble, the shell 11 at the desired finger hole area or areas 13 may be perforated and removed to provide the desired additional finger hole or holes in the desired position or positions.

5 A weight 14 is positioned at the center of the shell 11 substantially radially equidistant from said shell. The weight preferably comprises a metal mass of substantially spherical configuration. The weight 14 is supported in the shell 11, at the center thereof, by foam plastic material 16 which fills the shell between the weight and the shell. The foam plastic material is sufficiently rigid to maintain the weight 14 in position in the shell 11.

A recess, channel or groove 15 of substantially tubular configuration is formed in the foam plastic material 16 at each of the finger holes 12 and at each of the finger hole areas 13. Each recess 15 extends along a radius of the shell 11 and may be of substantially constant diameter or may taper down as it approaches the weight 14. Each recess 15 may extend for the entire radial length or for a part of such length.

10 The finger holes 12 and the finger hole area 13 are of the various sizes utilized in bowling balls to accommodate the different ball-gripping fingers of the bowler.

15 While the invention has been described by means of a specific example and in a specific embodiment, I do not wish to be limited thereto, for obvious modifications will occur to those skilled in the art without departing from the spirit and scope of the invention.

20 What I claim is:

30 1. A practice bowling ball, comprising a spherical shell of plastic material having a plurality of finger receiving holes formed therethrough, the thickness of said shell being substantially uniform throughout except for a plurality of removable finger hole areas therein in the vicinity of said finger holes, the thickness of said shell at each of said finger hole areas being substantially less than said uniform thickness to define reduced thickness areas adapted to be removed by a bowler; weight means positioned in said shell; positioning means between said weight means and said shell for maintaining said weight means in spaced relation to said shell, said positioning means including a finger receiving recess extending inwardly from each of said finger holes and removable areas, said holes, removable areas and recesses having such characteristics as to provide significantly different grips for a bowler.

35 2. A practice bowling ball as claimed in claim 1, wherein in said weight means is positioned at the center of said shell radially equidistant from said shell.

40 3. A practice bowling ball as claimed in claim 1, wherein in said positioning means comprises foam plastic material filling said shell between said weight means and said shell.

45 4. A practice bowling ball as claimed in claim 3, wherein in said weight means comprises a metal mass of spherical configuration positioned at the center of said shell substantially radially equidistant from said shell.
